(57) **CLAIM**

The ornamental design for a lubricant dispenser, as shown and described.

DESCRIPTION

FIG. 1 is a perspective view of the lubricant container of the present invention;

FIG. 2 is a first side view of the lubricant container of the present invention;

FIG. 3 is a second side view of the lubricant container of the present invention;

FIG. 4 is a front view of the lubricant container of the present invention;

FIG. 5 is a rear view of the lubricant container of the present invention;

FIG. 6 is a top view of the lubricant container of the present invention; and,

FIG. 7 is a bottom view of the lubricant container of the present invention.
